MOUNTING FOR ROTARY AGITATORS

Carl S. Brown, Lakewood, and Edward E. Deuring,
Cleveland Heights, Ohio, assignors to Glascole
Products, Inc., Cleveland, Ohio, a corporation
of Ohio

Application June 18, 1949, Serial No. 99,942

4 Claims. (Cl. 308—187.1)

1

This invention relates to a mounting for a rotary agitator and particularly to an improved mounting for rotary agitators of enclosed containers where the agitator drive and support is mounted on the exterior of the container.

The present invention is especially adapted for use in connection with enclosed, agitator equipped, containers, such as reaction kettles which are used in the manufacture of synthetic rubber and plastics and particularly where the contents of the kettle is corrosive and/or under pressure. Such reaction kettles generally comprise an enclosed container provided with a removable cover or integral top having a suitable covered opening. An agitator shaft generally extends vertically through the top of the container and is provided on its inner end with an impeller or other agitating means. An agitator driving unit, including a motor, is mounted on the top or cover of the kettle and is suitably connected with the agitator shaft to rotate the same.

In many instances the corrosive nature of the contents requires the application of a corrosive resistant material to the interior of the kettle, the agitator, and that portion of the agitator shaft which is in contact with such contents. A coating of glass which is fused to the surfaces to be protected has been found highly satisfactory for such purposes.

In the past considerable difficulty has been experienced in providing a satisfactory agitator shaft mounting, which would satisfactorily support the agitator shaft for rotation, eliminate undue strains on the glass coated parts, reduce friction and wear, permit the use of high internal fluid pressures, and temperatures, and at the same time be capable of withstanding heavy duty over protracted periods of time. These, therefore, are the general objects of the present invention.

Other objects and advantages of the present invention will be readily understood from the following specification, reference being made to a preferred embodiment of the invention as illustrated in the accompanying drawings. The essential features of the invention will be summarized in the claims.

Referring now to the drawings, Fig. 1 is a view of an agitator equipped reactor kettle embodying the present invention; Fig. 2 is an axial section through a portion of the agitator shaft and the associated parts of the kettle; Fig. 3 is a fragmentary view, partially in section, illustrating the portion of the rotary seal used to prevent escape

of the kettle contents along the agitator shaft; and Fig. 4 is a fragmentary sectional view through the drive shaft and gear housing, taken in the same plane as Fig. 2 but on a somewhat smaller scale.

In the drawings, 10 indicates a closed container such as a reaction kettle, which is supported in a vertical position by suitable legs 11. The kettle illustrated has an open top which, when in use, is closed by a top or cover 12. A suitable sealing gasket (not shown) is positioned between the cover and the kettle. Clamps 15 are provided to retain the cover in position. While the embodiment shown includes a removable cover 12, it is to be understood that the top of the kettle may be formed integral with the body thereof, and a suitable opening, indicated at 16, may be provided which may be sealed by a relatively small cover.

20 An agitator 17 is mounted on the lower end of a vertical shaft 20 which extends into the kettle through a flanged opening 21 in the cover. The agitator shaft is supported in part by and extends through a bearing and seal assembly generally indicated in the drawings at 25 and which is mounted on the top 12 and coacts with the flange 22 of the opening 21 and the agitator shaft 20 to prevent the escape of the fluid pressure within the kettle.

25

30 An agitator drive mechanism is also mounted on the kettle top 12. This mechanism is generally indicated at 26 and includes a housing 27 carrying a vertical extending drive shaft 28 which is supportingly and drivingly coupled with the agitator shaft 20 as will be hereinafter more fully described. The drive shaft 28 is driven by a motor 30 mounted on a platform 31 carried by the housing 27. The armature shaft 32 of the motor 30 is drivingly connected to the shaft 28 by suitable speed reduction gearing, indicated at 33 as being mounted within the housing 27.

As heretofore mentioned, the invention is particularly adapted for use in connection with reactors containing corrosive materials. Accordingly the kettle 10, which is made of metal such as steel, is provided with an internal glass coating 35, such coating being fused to the steel in the usual manner. The agitator 17 and its shaft 20 also are made of metal and provided with a glass coating 36 which is fused to the exterior thereof.

The agitator shaft 20, as heretofore mentioned, is supported by, and journalled in the bearing and seal assembly 25. This assembly comprises a tubular metallic sleeve or housing 40 having a

metallic ring 41 seated against the internal shoulder 42 in its lower end. The bottom and internal surfaces of this ring are provided with a fused glass coating 43. The housing 40 is secured in position on the kettle 10 by bolts 44. These bolts pass through enlarged openings 45 in a flange 46 of the housing 40 and threadingly engage bosses 47 which are welded to the top 12 of the kettle. A gasket 48 of resilient non-corrosive material is interposed between the lower surface of the ring 41 and the upper surface of the kettle flange 22, and provides a fluid tight seal between the kettle and housing. The glass lining 35 of the kettle extends over the upper surface of the flange 22 and prevents corrosive action at the junction of the housing 40 and the kettle.

The agitator shaft 20 is rotatably supported by the housing 40. The upper end of the shaft 20 is not glass coated and is provided with an anti-friction bearing 50. This bearing is shown as being a double tapered roller bearing, the inner race of which is clamped against a shoulder 51 formed on the shaft 20, by a nut 52 which engages the external threads of a split sleeve 53 seated in a channel 54 formed in the shaft 20. The outer race 55 of the bearing 50 is clamped against a shoulder 56, formed on the inner wall of the housing 40, by a cap 57 which is secured to the housing 40 by bolts 58.

Escape of fluid from the kettle along the agitator shaft 20 is prevented by a rotary seal generally indicated at 60. As illustrated in Fig. 2, this seal comprises a compressible sealing ring 61 of non-corrosive material which is clamped against a glass coated region of the shaft 20. However, this ring may be glass coated, in which case the surface contacting the ring 61 is ground to provide an efficient bearing surface. Likewise the surface of the insert 41 may be glass coated and ground to provide effective bearing and sealing surfaces. As illustrated, the sealing ring 61 is seated in an upwardly facing channel 65 formed in a ring 62 which loosely encircles the shaft 20. The ring 62 is rotatably seated on an annular gland or inset 63 preferably made of carbon, a material which is inert to most corrosive actions and provides an ideal sealing surface. The insert 63 seats against a shoulder 64 formed in the retainer ring 41.

The packing or sealing ring 61 is held in position in the channel 65 by a clamping ring 68 which freely encircles the shaft 20 and enters the channel 65 seating against the packing 61. The packing engaging surfaces of the rings 62 and 63 are beveled so that when brought together axially they force the packing into clamping engagement with the shaft 20. This clamping action is caused by a series of springs 69 which are interposed between the ring 68 and an upper ring 70 spaced thereabove and secured to the shaft 20 by set screws 71.

The rings 70, 68, 62, together with the seal 61, rotate as a unit with the shaft 20. The upper ring is secured to the shaft by set screws 71 and carries pins 72 which engage openings 73 in the ring 68. The ring 68, in turn, is provided with radial extending pins, one of which is shown at 74 in Fig. 3, and which engage slotted openings 75 in the ring 62. The coating surfaces of the lower ring 62 and the carbon insert 63 provide an ideal seal and bearing for the sealing unit 60. If desired, the ring 62 may be protected by a glass coating on its inner face. However, generally it

is illustrated as being made of a suitable non-corrosive alloy.

The cap 57 is hollow and is provided with a seal generally indicated at 80. This seal is similar to the seal 60 and hence will not be described in detail, and the individual components corresponding with those of the lower seal 60 are indicated by the same reference characters. The upper seal packing 61 bears against the shaft 20 above the glass coating thereof and the insert ring 41 has been omitted, and the insert 63 is seated in the cap itself.

The glass coating 36 of the agitator shaft 20 extends above the sealing ring 61 of the seal 60. Accordingly, this seal engages such coating, thus reducing the exposed surfaces which are unprotected by glass. The glass coating 36 of the agitator shaft 20 in the region of the lower seal is ground as indicated at 23. This grinding of the glass coat insures a trueness of the shaft, not otherwise obtainable, and, in addition, provides a surface which may be advantageously sealing by the packing 61 and yet which will permit axial movement of the packing. By providing the shaft 20 with an exceedingly true surface the rings 70, 68, and 63, may be made to provide a minimum amount of clearance with the shaft 20 without danger of contact therewith. The ground surface of the glass likewise increases the sealing adhesion between the seal 61 and the shaft.

The agitator shaft is driven by the drive unit 28 which is mounted on the cover 12 with its drive shaft 28 in vertical alignment with the agitator shaft 20 and extending into the upper end thereof. The drive housing 27 is provided with a plurality of legs 93 which are secured to the upper end of a cage-like structure 91 by bolts 92. The cage 91 encircles the bearing assembly 25 and is secured to the cover by studs 93. These studs engage threaded openings in bosses 94 which are welded to the kettle top 12. These studs 93 extend through sleeves 104 which are threaded to the cage 91, and are provided with suitable nuts 96. Accordingly, the axis of the drive shaft 28 may be tilted to bring its axis parallel with the axis of the agitator shaft 20. To insure alignment of the agitator shaft with the drive shaft 28 the shaft bearing assembly 25 is adjustable transversely of its axis. As heretofore mentioned, the mounting studs 44 pass through enlarged openings 45 in the housing 40, thus enabling transverse positioning of the housing together with the agitator shaft. Suitable adjusting screws, one of which is indicated in Fig. 2 at 95, pass radially through the housing 40 and engage the periphery of the flange 22 of the kettle top 12, thus accurately positioning the housing to complete the alignment of the shafts.

The drive shaft 28, as indicated in Fig. 4, is journalled in a pair of spaced bearings 96 and 97 carried by the housing 27. This shaft projects downward into snug telescopic engagement with the hollow upper end of the agitator shaft 20, and the driving connection therebetween is established by a key 98 and a set screw 99 (Fig. 2). The lower bearing 97 is elongated and is spaced some distance above the agitator seal and supporting unit, thus providing a sturdy upper bearing for the agitator shaft.

The agitator shaft 20 is hollow and is sealed at its upper end by the drive shaft 28. The upper bearing of the agitator shaft, namely the bearing 97 of the drive shaft 28, is spaced above the seal unit 25. Likewise the housing 27, which supports the bearing 97 and shaft 28, is spaced

from the seal unit and is connected to the kettle by the open cage-like structure 91, thus reducing, to a minimum, the transfer of heat from the kettle to the bearing 97. This arrangement reduces the effect of high temperatures in the kettle on the agitator shaft drive and supporting mechanism and thereby greatly increases the efficiency of the structure.

The housing 40 provides a container for lubricant to lubricate the bearing 50 and the seal members 60 and 80. When the kettle is used for high internal pressures, such pressures may be balanced by maintaining the circulation of oil through the housing 40 at pressures commensurate with the internal pressure of the kettle. To this end the housing 40 is provided with an opening 100 for an inlet conduit 101, and the cap 57 is provided with an opening 102 for an outlet conduit 103. These conduits may be connected with a reservoir and pressure pump in the usual manner to maintain the circulating pressure of the lubricating fluid. If desired, the usual filters may be used in the lubricating system.

When the unit is used with low internal kettle pressures, the upper seal 80 in the unit 25 may be eliminated, and the openings 100 and 102 plugged. The elimination of the upper seal 80 increases the space provided in the housing 40 for a lubricant supply.

I claim:

1. In an agitator bearing support for reaction kettles and the like, a housing encircling said shaft, a rotary seal mounted in one end of said housing, a retainer ring for said seal at the end of said housing and having its under and inner surfaces provided with a glass coating, said seal including a packing ring engaging and rotatable with said shaft to provide a fluid tight seal therebetween, said shaft having a glass coating provided with a ground surface to coat with said packing material, and an antifriction bearing mounted in said housing above said seal and coacting with said shaft to rotatably support said shaft in said housing.

2. A mounting unit for an agitator shaft for containers having a top provided with an opening and through which the agitator shaft extends, said unit comprising a housing encircling the shaft and secured to said top in alignment with the opening in the container, a rotary seal mounted in the lower end of said housing and including a packing ring engaging said shaft to provide a fluid tight seal, said shaft having a glass coating provided with a ground surface to coat with said packing, and an antifriction bearing carried by said housing above said seal and coacting with said shaft to rotatably support said shaft in said housing.

3. In a mounting unit for an agitator shaft

for a reaction kettle having an opening in its top, through which the agitator shaft extends, said unit comprising a housing encircling said shaft externally of said kettle and adapted to be secured to said top in alignment with the opening therein, an annular insert holder encircling said shaft and clamped between said housing and top, a gland insert mounted in said insert holders within said housing, a rotary seal mounted in said housing and coacting with said gland to form a fluid tight seal therewith, said rotary seal including a packing ring engaging said shaft to provide a fluid tight seal therewith, a glass coating on said shaft provided with a ground surface to coat with said packing, an antifriction bearing carried by said housing above said seal and coacting with said shaft to rotatably support said shaft in said housing, and a second rotary seal mounted in said housing above said bearing.

4. In a mounting unit for an agitator shaft for a reaction kettle having an opening through which said shaft extends, said unit comprising a housing encircling said shaft and secured to the container top in alignment with the opening therein, a rotary seal mounted in said housing at the lower end thereof and including an annular retainer clamped between said housing and said container top, a gland insert surrounding said shaft and mounted in said retainer, a ring encircling said shaft and axially movable relative thereto and having its lower face coacting with the upper face of said insert to provide a rotary fluid tight seal therebetween, a second ring encircling said shaft and axially movable relative thereto, packing disposed between said rings and engaging said shaft to provide a fluid tight seal therebetween, resilient means to urge said rings and packing toward said insert, and means to rotate said rings and packing as a unit with said shaft, said shaft having a glass coating provided with a ground surface to coat with said packing material, and an antifriction bearing carried by said housing and coacting with said shaft to rotatably support said shaft in said housing.

CARL S. BROWN.
